C. P. EAGER.

PARALLEL PROTRACTOR.

APPLICATION FILED JAN. 20, 1912.

Patented Jan. 28, 1913.

UNITED STATES PATENT OFFICE.

CHARLES P. EAGER, OF RENO, NEVADA.

PARALLEL PROTRACTOR.

1,051,712.

Specification of Letters Patent. Patented Jan. 28, 1913.

Application filed January 20, 1912. Serial No. 672,284.

To all whom it may concern:

Be it known that I, CHARLES P. EAGER, a citizen of the United States, and a resident of Reno, in the county of Washoe and State of Nevada, have invented a new and Improved Parallel Protractor, of which the following is a full, clear, and exact description.

This invention relates to protractors, particularly to quick acting protractors, and has for an object the provision of improved means whereby any angle may be quickly and accurately found.

Another object of the invention is the provision of an improved structure in a protractor which will permit the protractor to be adjusted for forming parallel extensions whereby lines may be drawn several times the length of the protractor while remaining in its original position.

A still further object of the invention is the provision and arrangement of improved means designed to engage the board or paper on which the device is mounted, associated with movable means and a measuring indicator whereby the device may be swung around a given point and caused to occupy any desired angle to its original position, such angle being disclosed on the indicator.

In carrying out the objects of the invention, a suitable base is provided, to the edges of which are secured straight edges or rules designed to be shifted longitudinally of the body for permitting lines to be drawn beyond either end of the body without moving the device. Arranged near one end of the body of the device is a construction including a pin designed to be pressed into the table or paper, for acting as a fixed pivot around which the device may be swung for securing an angle. In order to know what angle is being secured, a rotating traction device is provided, formed with an indicating mechanism so that the angle will be indicated thereon as the device is moved.

A practical embodiment of the invention is represented in the accompanying drawings forming a part of this specification, in which similar characters of reference indicate corresponding parts in all the views.

Figure 1 is a top plan view of an embodiment of the invention; Fig. 2 is a bottom plan view of the device shown in Fig. 1,

one of the straight edges extending beyond one end of the body of the device; Fig. 3 is a side view of the structure shown in Fig. 1, the same being shown on an enlarged scale and certain parts broken away; Fig. 4 is a section through Fig. 3 approximately on the line 4—4; Fig. 5 is a section through Fig. 4 approximately on the line 5—5; and Fig. 6 is a section through Fig. 3 on the line 6—6.

Referring to the accompanying drawings by numerals, 1 indicates a body formed of any desired material, to which the various moving parts are connected. Arranged on each edge of the body 1 is a dovetailed groove in which dovetailed tongues 2 are slidably positioned, which are formed preferably integral with the straight edges 3 and 4, whereby the straight edges are connected with the body 1, but are permitted a free longitudinal movement. The upper and lower surfaces of the dovetailed tongues 2 are arranged parallel with the upper and lower surfaces 5 and 6 of the straight edges 3 and 4 whereby the straight edges may be turned over whenever desired. This is important as it permits graduations to be provided on each side of the straight edges, and consequently four sets of graduations for only two straight edges. In order to properly operate the straight edges, suitable thumb members 7 and 8 are provided which are threaded into the respective straight edges so as to be readily removed and inserted from the opposite side when the straight edges are turned over.

One end of the body 1 is provided with a slot 9 having a countersunk portion 10. Arranged to slide in the slot 9 is a post 11 threaded at 12 and bifurcated at its upper end for receiving an eccentric lever 13. The post 11 is provided with a projecting flange 14 which fits into the countersunk portion 10 in order to prevent the post from being removed by an upward movement thereof. A nut 15 is screwed over the threads 12 for clamping the post 11 rigidly to the body 1, and a locking set screw 16 is mounted on the nut 15 for preventing the nut 15 from slipping or becoming dislocated. The post 11 is provided with a central bore 17, in which is fitted a reciprocable pin 18 formed with a central bore for receiving a needle 19. A set screw 20 is threaded into the pin 18, as shown in Fig. 5, for clamping the needle 110

19 rigidly into place. The needle 19 is designed to continually project a short distance below the bottom of the pin 18 so as to enter or pierce the paper on which the device is mounted, while the pin 18 merely presses against the paper. Upon a downward movement of the handle 21 of the lever 13, the pin 18 will be depressed until the needle 19 has entered the paper and any further movement of the handle 21 will cause the end 22 of the device to be raised and consequently cause a traction roller 23 to become disengaged from the paper. The raising of the end 22 will not raise the roller 24 or the end 25. When the end 22 has been raised, the end 25 may be swung around in the arc of a circle or for a complete circle, as desired, as hereinafter described.

Secured to the body 1 are supports 26 and 27 formed preferably in two parts and secured to the body 1 in any desired manner, as for instance by screws. The parts of the supports 26 and 27 are clamped together by screws or bolts 28 and 29 so as to firmly clamp journal pins 30 and 31. Each of these journal pins is formed with a conical end fitting in a conical socket in a shaft 32. The shaft 32 has rigidly secured thereto the traction rollers 23 and 24, and is protected by a suitable housing 33 secured to the body 1 in any desired manner. The traction rollers 23 and 24 are preferably corrugated or slightly cogged so that the same will positively turn when moved over the paper or other surface on which the device is being moved. Connected to the shaft 32 in the center or at any other desired point, is a beveled gear 34 which meshes with a beveled gear 35. The beveled gear 34 is held in place by a spring 36 and may be adjusted for any desired position. The beveled gear 35 is rigidly connected with a shaft 37 which is mounted in a bearing 38. Rigidly connected to the upper end of the shaft 37 is a supporting block 38 which has connected therewith an indicating arrow 39 which is adapted to move over the graduations 40 of a dial 41.

In operation when it is desired to draw a line at a certain angle from a given line, say at an angle of 20° , one edge of the protractor is placed parallel with the given line and then the handle 21 depressed so that the needle 19 will enter the paper and the pin 18 will cause the end 22 of the protractor to rise. The end 25 is then grasped and moved pivotally until the dial 41 indicates that the device has swung around 20° . The handle 21 is then raised until the pin 18 and needle 19 have become disengaged from the paper. After this the entire device is pushed toward the given line in substantially a direction opposite to that which the device has just previously traveled. The device is pushed until the edge thereof has

reached any particular point from which it is desired to extend the 20° angle.

In order to test the device so as to be positive that the same is correct, the lever is depressed as above described after a line has been previously drawn parallel with the center of the straight edges, and then the device swung around for a complete circle. When the dial 41 indicates that the device has traveled 360° , if the straight edge is correctly positioned against the line originally drawn, then the device is correct. If the straight edge has passed the line originally drawn the nut 15 is loosened and the post 11 moved longitudinally in the slot 9 in a direction away from the end 25. This will cause the roller 24 to travel in a larger circle. After the device has been again tested, the post 11 may be again adjusted, and so on until the device is absolutely correct.

Having thus described my invention, I claim as new and desire to secure by Letters Patent:—

1. In a protractor, a body portion, a pair of traction wheels therefor formed with corrugations on their peripheries for preventing slipping, a reciprocable pivotal pin mounted on one end of said body portion, a cam pivotally connected with said body portion and engaging said pin for pressing on the top thereof, said cam being of such a size as to cause said pin to project below said body portion and raise the end of the body portion carrying said pin whereby the opposite end of said body portion may be swung around through any desired angle, and means operated by the traction wheels near the end opposite said pin for indicating the number of degrees said body portion has been swung.

2. In a protractor, a body portion, a pivotal pin arranged near one end of said body portion, means for raising said pivotal pin, and for lowering the same to such an extent as to cause an elevation of the end of the protractor, a traction wheel arranged at the opposite end of said body portion to said pivotal pin, and indicating means associated and co-acting with said traction wheel for indicating the angle through which the protractor has been moved when the same has been swung on said pivotal pin.

3. In a protractor, a body portion, a reciprocable pivotal pin, means mounted on said body portion and engaging said reciprocable pivotal pin for forcing the pivotal pin downward and the ends of said body portion upward, a traction wheel arranged at the opposite end of said body portion to said pivotal pin, a shaft rigidly secured to said traction wheel, an indicating member, and means for connecting said indicating member and said shaft, whereby when the protractor is moved pivotally

around said pivotal pin, said traction wheel will rotate and said indicating member will be moved.

4. In a protractor, a body portion formed 5 with a slot in one end, a post mounted in said slot, means for clamping said post to said body portion at any point along said slot whereby the distance of the post from the opposite end of said body portion 10 may be varied, a reciprocable pivotal pin mounted in said post, a pivotally mounted lever structure engaging said pin and forcing the same downward and the end of said body portion upward, a traction wheel arranged 15 at the opposite end of said body portion to said slot, and an indicator connected with said traction wheel for indicating the degree of rotation of said body portion around said pivotal pin.
- 20 5. In a protractor, a body portion, a pivotal pin, means for simultaneously forcing the pin downward and the end of the body portion upward, a traction wheel arranged

at each end of said body portion, the traction wheel at the end in which the pivotal pin is mounted being raised when said end has been raised, a shaft for rigidly connecting said traction wheels, an indicating arm, and means for operatively connecting said indicating arm with said shaft whereby said indicating arm is rotated at a certain ratio to rotation of said traction wheel mounted at the end of said body portion opposite said pivotal pin, said pivotal pin being adapted to be raised and said body 30 portion moved bodily laterally with both wheels in engagement with the supporting surface when it is desired to draw a line at an angle to a given line.

In testimony whereof I have signed my 40 name to this specification in the presence of two subscribing witnesses.

CHARLES P. EAGER.
